UNITED STATES PATENT OFFICE.

ALFRED H. KNIGHT, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,131,936.

Specification of Letters Patent. Patented Mar. 16, 1915.

Application filed April 15, 1912. Serial No. 690,783.

To all whom it may concern:

Be it known that I, ALFRED H. KNIGHT, a citizen of the the United States, and resident of Detroit, county of Wayne, State of Michigan, have invented certain new and useful Improvements in Hydrocarbon-Motors, of which the following is a specification.

This invention relates to hydrocarbon motors and more particularly to the ignition systems thereof.

In the use of hydrocarbon motors for motor vehicles and motor boats, it is customary to provide both a battery and a magneto for the ignition. The current generated by the battery and the magneto is usually conducted to a transformer coil which raises the voltage so that high tension current is available for producing sparks in the cylinder. The high tension current is led from the transformer coil through a distributor which is usually associated with the magneto and which distributes the current to the different cylinders. In many systems it is customary to provide switches in the circuits leading to the spark plugs of the cylinders, for the purpose of conveniently cutting out one or more of the cylinders in making tests on the motor. It has been found that when the motor is running with any of these switches open, there being no outlet for the high tension current, the voltage tends to build up to such an extent that there is danger of breaking down the insulation in the transformer coils or other parts of the high tension circuit. In arranging the ignition circuits one side of each circuit is usually grounded on the motor frame and cylinders, and in the present invention in order to avoid the danger of breaking down the insulation when any of the switches are open, I have provided means for grounding the switches on the motor cylinder when they are opened.

The novel features of the invention will be apparent from the following description taken in connection with the accompanying drawings in which,

Figure 1 is a fragmentary elevation of the upper part of a four-cylinder hydrocarbon motor; Fig. 2 is a side elevation of one

of the switches shown in Fig. 1, on an enlarged scale; Fig. 3 is an elevation showing a modification of the invention; Fig. 4 is an end elevation of Fig. 3.

55

Referring to the drawings, 10 and 11 indicate the cylinder castings, the cylinders being preferably cast in pairs and each cylinder provided with a spark plug. In Fig. 1 these spark plugs are indicated by the numerals 12, 13, 14 and 15. The cylinders are preferably water jacketed and provided with outlets 16 for the purpose of discharging the water from the jackets to a suitable conduit leading to the radiator or other cooling device.

60

Any preferred form of ignition system may be used such as that described in the patent to Loomis No. 1,011,977, dated December 19, 1911. For the purpose of illustration I have shown in Fig. 1 a system of conductors in which 17 may be a high tension conductor leading from the transformer coil (not shown) to the distributor (not shown) and 18 may be the low tension conductor leading from the magneto (not shown) to the primary coil of the transformer. From the distributor conductors 19, 20, 21 and 22, lead to the spark plugs 12, 13, 14 and 15 respectively. In the spark plug circuits I arrange suitable switches and as shown in the drawings I have indicated these switches as contacting directly with one terminal of the spark plugs. This terminal is connected with one electrode of the plug and the other electrode is usually attached to a shell or a metallic part of the plug constituting the other terminal with which the ignition circuit is electrically connected.

70

90

For the purpose of supporting the conductors and the switches, the cylinders may be provided with upwardly extending brackets 23 to which are secured the insulators 24 in any suitable manner, as by means of the screws 25. The insulators 24 may be provided with openings 26 for the conductors. Each of the insulators 24 carries, preferably at the top thereof, a bracket 27 to which may be pivoted a member 28, the latter having pivotally connected therewith a switch 29, the pivot of said switch being

95

100

preferably arranged at right angles to the pivot connecting the member 28 and the bracket 27. This arrangement permits the switch 29 to have practically a universal 5 movement. The switch 29 comprises two spaced side plates which are secured to a handle 30 and which are adapted to engage the sides of the terminal 31 of the spark plug.

10 In the form of the invention illustrated in Fig. 2, an arm 32 may be mounted on the insulator 24 and secured thereto by means of one of the screws 25, so that the screw will constitute an electrical connection between the arm and the bracket 23. The arm 32 may extend upwardly and have at its upper end an arc-shaped portion 33 which is adapted to be engaged by a downwardly projecting finger 34 on the member 28, when the latter is swung on its pivotal connection with the bracket 27, in lifting the switch 29 out of contact with the terminal 31. The relation of the portion 33 of the arm 32 and the finger 34 is such that the finger will 20 contact with the portion 33 just before or immediately after the switch 29 moves out of contact with the terminal 31. When the finger 34 is in contact with the arm 32, the current is short circuited to the ground connection and all liability of burning out the insulation of the transformer coils is eliminated.

25 In the modification shown in Figs. 3 and 4, the switch 29 may be of the same construction as that shown in Fig. 2, but the short circuiting device is somewhat different and consists of a bracket 35 which is preferably secured to the cylinder casting by means of the spark plug and extends upwardly along the side of the latter and has at its top a downwardly projecting U-shaped portion 36 which is arranged directly above the switch 29 so that it will be engaged by the switch immediately after the switch 30 moves out of contact with the spark plug terminal 31.

35 In both of the modifications illustrated, the insulator 24 may be provided at its top with a binding post 37 which is electrically connected with the bracket 27 and forms a point of attachment for the high tension conductor.

40 While I have illustrated two forms of the invention, it will be readily understood that the invention may be carried out in various ways which come within the scope of the appended claims and therefore I do not wish to be limited to the details of construction shown and described.

45 Having thus described my invention what I claim is,

1. In a hydrocarbon motor provided with a spark plug and an ignition circuit connected with the spark plug, the combination 50 of means for opening and closing said igni-

tion circuit, and means whereby the circuit opening and closing means is adapted to short circuit the ignition current around said spark plug when the ignition circuit is open.

70 2. In a hydrocarbon motor provided with a spark plug and an ignition circuit connected with the spark plug, the combination of a switch for opening and closing said circuit, and means adapted to be engaged by said switch when in open position whereby the current is short circuited around the spark plug.

75 3. In a hydrocarbon motor provided with a spark plug and an ignition circuit, the combination of a switch in said circuit and adapted to engage one terminal of the spark plug, and a short circuiting device electrically connected with the other terminal of the spark plug and adapted to be engaged by said switch when the latter is moved out of engagement with the spark plug.

80 4. In a hydrocarbon motor provided with a spark plug, having one terminal thereof grounded on the motor cylinder, the combination of a switch, an ignition circuit having one side thereof grounded on said cylinder and the other side thereof connected with said switch, and a short circuiting device grounded on said cylinder, said switch being adapted to be moved into engagement with said spark plug and said short circuiting device.

85 5. In a multiple cylinder hydrocarbon engine having a spark plug for each cylinder and a separate ignition circuit for each spark plug, the combination of independent devices for opening and closing each of said circuits, and means whereby the circuit opening and closing devices are adapted to short circuit the ignition current around the spark plugs when their circuits are open.

90 6. In a multiple cylinder hydrocarbon engine having a spark plug for each cylinder and a separate ignition circuit for each spark plug, the combination of independent switches in each of said circuits, and means adapted to be engaged by the switches whereby the ignition current may be short circuited around the spark plugs.

95 115 7. In a hydrocarbon motor provided with a spark plug and an ignition circuit, the combination of a switch in said circuit adapted to engage one terminal of the spark plug, and a member in fixed relation to the spark plug and electrically connected with the other terminal thereof and adapted to be electrically connected with the switch when the latter is moved out of engagement with the spark plug terminal.

120 125 8. In a hydrocarbon motor provided with a spark plug and an ignition circuit, the combination of a switch in said circuit adapted to engage one terminal of the spark plug, an arm held in fixed relation to the

spark plug and electrically connected with the other terminal thereof, and means electrically connected with said switch and adapted to be moved into contact with said 5 arm when the switch is moved out of engagement with the spark plug terminal.

In testimony whereof I affix my signature in presence of two witnesses.

ALFRED H. KNIGHT.
